UNITED STATES PATENT OFFICE.

EDWARD W. GROGAN, OF BYERS, TEXAS.

QUICK-ADJUSTING WRENCH.

1,269,275.

Specification of Letters Patent. Patented June 11, 1918.

Application filed February 6, 1918. Serial No. 215,637.

To all whom it may concern:

Be it known that I, EDWARD W. GROGAN, a citizen of the United States, residing at Byers, in the county of Clay and State of Texas, have invented certain new and useful Improvements in Quick-Adjusting Wrenches, of which the following is a specification:

This invention relates to improvements 10 in wrenches of the quick-action form, and has for one of its objects to simplify and improve the construction and increase the efficiency and utility of devices of this character.

15 Another object of the invention is to provide a device of this character in which provision is made for instantly releasing or locking the movable jaw in place relative to the stationary jaw.

20 Another object of the invention is to provide a device of this character including a locking lever having a cam face for applying pressure to hold the sleeve in locking relation to the stock, and combined yielding 25 means for holding the locking means to control the movements of the locking lever.

With these and other objects in view, the invention consists in certain novel features of construction, as hereinafter shown and 30 described and then specifically pointed out in the claim; and in the drawings illustrative of the preferred embodiment of the invention—

Figure 1 is a side elevation of the improved implement with the parts in locked 35 relation.

Fig. 2 is a view similar to Fig. 1 with the combined movable jaw and sleeve in section and the locking lever in open or released position.

Fig. 3 is an edge view of the part shown in Fig. 1.

Fig. 4 represents the clip device with the parts separated.

45 The improved wrench comprises a stock 10 having a plurality of ratchet teeth 11 on one edge, a stationary jaw 12 at one end and a solid handle 13 at the other end, the stock and its handle and the stationary jaw 50 being preferably cast in one piece. Slidably disposed upon the stock is an opposing or movable jaw 14 and having a sleeve portion 15 likewise slidably engaging the stock. Formed through the portion of the sleeve 55 farthest from the jaw 14 is a transverse socket, indicated at 16, to receive a stop

member 17 with a knife-edge 18 to engage the teeth 11 one at a time. The stop 17 is preferably slightly dove-tailed and the socket is correspondingly dove-tailed, and 60 slightly smaller at one end to enable the stop to be held firmly in position by friction only. A detachable stop pin 30 is applied to the stock 10 to prevent the displacement of the movable jaw.

65 Pivoted at 20 between the side walls of the sleeve is a locking lever, indicated as a whole at 21, and extending to a position opposite the handle 13, so that the same hand which clasps the handle may likewise 70 clasp the lever. The locking lever includes a cam face 22 at the side next to the stock and a stop recess 23 at the side opposite to the cam face. By this arrangement it will be obvious that when the lever 21 is moved 75 toward the stock 10 and the handle 13, the cam face 22 will engage the adjacent face of the stock and cause the knife-edge 18 of the stop 17 to engage with the adjacent tooth 11, as shown in Fig. 1, and thus firmly lock the 80 sleeve and its jaw 14 in position upon the stock.

Bearing upon one face of the sleeve is a clip 85 device including a base portion 24 having limiting ribs 25 and a bearing plate 26. Disposed between the ribs 25 and bearing 90 upon the base 24 are a plurality of superposed resilient holding members 27. The plate 26 is disposed externally of the holding members 27 and between the stop ribs 95 25, and all of the parts retained in position by a fastening screw or like device 28 which passes through the members 26, 27 and 24 and into the body of the sleeve as shown more particularly in Fig. 2. At their free 95 ends the members 27 are curved slightly toward and normally engage the adjacent face of the lever 21, as shown in Fig. 1, and thus maintain the cam face 22 normally in its locking relation to the stock 10 and holding 100 the stop 17 in locking relations with the teeth of the stock. At their free ends the members 27 are designed to engage in the stop recess 23 when the lever 21 is disposed in its open or releasing position as shown in 105 Fig. 2, and thus limit the outward movement of the lever and prevent abnormal movement which would otherwise cause the extended free end 29 of the lever to engage the stock and force locking engagement of 110 the sleeve with the stock. The presence of the stop recess 23 in coacting relation to the

holding members 27 is thus an important feature of applicant's device, and materially increases its efficiency and utility.

The confronting faces of the jaws 12-14 5 may be provided with pipe or rod-engaging teeth 31, if preferred, to enable the implement to be adapted as a pipe or rod wrench.

The improved implement is simple in construction, can be constructed of any required 10 size or of any suitable material.

When once locked in position the movable jaw and its sleeve are so firmly held in place that they will not yield under strain and thus cause a nut to be wedged between the 15 jaws. The jaw 14 and its sleeve and attachments may be readily detached by removing the holding pin 30 and slipping the handle 13 from the stock and the handle.

Having thus described the invention, what 20 is claimed as new is:

A wrench comprising a stock having a

Copies of this patent may be obtained for five cents each, by addressing the "Commissioner of Patents, Washington, D. C."

plurality of teeth and a rigid jaw, a sleeve 25 slidable upon the stock and having an opposing jaw, a stop carried by the sleeve and engageable with the teeth, a lock lever pivoted in the sleeve and including a lock recess and a cam face adapted to move the sleeve laterally to cause the stop to engage one of the teeth, a clip device including a base member having side ribs and a clamp member, a plurality of resilient members superposed between the base member and its ribs and engaged by the clamp member, and a fastening device operating through the clamp member, resilient members and the 30 base and into the sleeve, said resilient members adapted to normally maintain the cam face in engagement with the stock and to engage in the lock recess and limit the outward movement of the lever.

In testimony whereof I affix my signature.

EDWARD W. GROGAN. [L. s.]
